UNITED STATES PATENT OFFICE.

HERMAN MUEHLE, OF CLEVELAND, OHIO.

HATPIN.

1,424,666.

Specification of Letters Patent. Patented Aug. 1, 1922.

Application filed July 24, 1920. Serial No. 398,688.

To all whom it may concern:

Be it known that I, HERMAN MUEHLE, a citizen of the German Republic, residing at 10506 Crestwood Ave., in the city of Cleveland, county of Cuyahoga, and State of Ohio, have invented a new and useful Improvement in Hatpins, of which the following is a specification, the principle of the invention being herein explained and the best mode in which I have contemplated applying that principle, so as to distinguish it from other inventions.

My invention relates to a hat pin, and more particularly to a device including fastening contrivances for constantly holding the pin in movable connection with the hat.

One object of my invention is to avoid the likelihood of misplacement or loss of the hat pin. Another object is to enable effective use of the pin without having a pointed end project laterally beyond the crown of the hat.

I am aware that devices of this kind have been previously originated, but believe that mine presents certain advantageous features to be hereinafter explained.

Adverting to the drawings:

Figure I is a horizontal section through the crown of a hat looking downwardly, such crown being equipped with a hat pin embodying my invention.

Figure II is a vertical section through a hat equipped with my invention.

Figure III is an elevation of my preferred form of hat pin.

Figure IV is a plan view of one detail or accessory with which the hat pin is to cooperate.

Figure V is a side elevation of Figure IV.

Figure VI is a plan view showing certain parts of Figure IV in an altered position.

Figure VII is a section on line VII—VII of Figure VI.

Figure VIII is a section on line VIII—VIII of Figure VI.

Figure IX is a side elevation of another accessory with which the hat pin is to cooperate on the opposite side of the hat.

Figure X is a front elevation of Figure IX.

Figure XI is an enlarged section on line XI—XI of Figure X.

Figure XII is an enlarged section on line XII—XII of Figure XI.

Figure XIII is an enlarged section on line XIII—XIII of Figure X.

Figure XIV is a broken elevation of one end of a modified form of hat pin.

Figure XV is an enlarged broken section corresponding to Figure XI with locking wire removed to show construction more clearly.

Figures XVI and XVII are a plan view and a section respectively of a modified form of accessory for cooperation with the insertable end of the hat pin.

Figure XVIII is a broken sectional view of a portion of a hat equipped with the modified accessory shown in Figures XVI and XVII.

A hat includes a rim 1 and a crown 2. A hat pin 3 includes at one end a spherical head 4, and at its other end is provided with two smaller spherically shaped portions 5.

It is to be understood that I propose to have my hat pin pass through only one side of the crown of a hat and to be there held in position by a suitable guiding structure which I preferably make adjustable. Instead of having the other end of the pin pointed, I propose to have its end fashioned so as to enable its holding engagement with another structure to be secured in any position, as may be desired by the wearer.

The guiding structure is illustrated in Figures IV to VIII inclusive and may be a stamping which comprises two circular parts attached together and adapted to be bent around into juxtaposition. Such stamping 7 may be of spring brass but in any event should be flexible, includes one circular part 8 having a concavo-convex central portion 9 and four circumferentially arranged sew-holes 10 therearound. The rim of the part 8 is also provided with three flexible prongs 11. The concavo-convex portion 9 is supplied with a series of holes 12. The other circular part 13 is ring-shaped and is likewise provided with four sew-holes 14. Extending diametrically across the ring 13 is a flexible strip 15 which carries two transversely curled tubular portions 16 and 17 of a size sufficient to enable the insertion therein of the shank 3 of the hat pin. It is to be

understood that the strip 15 may be twisted back and forth whenever a hat pin which occupies the tubular portion 16 and 17 is turned back and forth. Such alternative adjustment is clearly suggested in Figure I in the full and dotted line positions of the hat pin with reference to the crown of the hat. The purpose of this is to enable a lady to position the hat pin in any preferred direction through her hair depending upon the style of coiffure which happens to be in vogue.

The other part which is purposed to engage and hold the extremity of the hat pin is shown in Figures IX to XIII inclusive. It may likewise be formed as a metal stamping with one part 18 curved to conform to the hat band and provided with sew-holes 19 whereby it may be secured in any desired location with reference to the guiding part 7. The securing part includes raised sides 20 highest at one end 21 and having a front face declining along a curve 22 as is well shown in Figure IX. The face 22 is fashioned with a row of circular depressions 23 to form spaces 24 which clearly appear in Figure XIII and each of which is adapted to accommodate with a snug fit or spring action the spherical part 5 on the hat pin. To further resist unintentional dislodgment of the end of the hat pin I have supplied the facing with a zigzag shaped length of wire 25 so positioned that two substantially parallel sections extend across each of the spaces 24. The parallel sections of the wire 25 will be adapted to spring apart in response to the pressure of the end of the hat pin thereagainst and to then assume their normal position to one side or the other endwise of the spherical enlargement 5.

The parts of the stamping 7 are to be folded against each other and then the prongs 11 bend around the outer rim of the ring 13 as shown in Figure VI. Thereafter the tubular portions 16 and 17 may be tilted as shown in Figures VII and VIII. In operation the ball 4 is grasped by the hand and moved laterally to twist the strip 15 until the end of the hat pin assumes the desired one of the three angular positions in line with one of the holes 12, whereupon it is pushed through the hair and caused to enter, by means of the sense of touch, one or the other of the spaces 24 in the plate 18 presumably positioned to suit, in which position the pin is held locked by the spring action of the sections of the wire 25.

Or in sewing the member 7 on the hat the tubular portions are tilted until they assume the desired angle, then the member 17 is pushed through an opening made to suit in the hat, and the member 7 appropriately sewed on to the hat. Thereafter, no

more tilting or twisting of the strip 15 is required, unless otherwise mounted by choice. This position of the angle of 16 and 17 which is thus fixed guides the pin in the proper direction so that the wearer 70 will automatically push the pin toward the member 18.

Figure XIV is a view corresponding to Figure XI with the omission of the additional binding means consisting of the wire 75 25 which will be seen to be omitted, in which event the spherical section 5 is to be merely held by frictional engagement.

In substitution for the stamping 18 I propose the modification consisting of a ring 80 26 provided with sew-holes 27 and carrying a hemi-spherical wire netting 28, the meshes of which are such as to enable one or the other of the different size spherical ends 29 of a modified hat pin 30 to be pressed 85 therethrough and to be detachably held thereby in the position shown in Figure XVIII. The double spherical end 29 is desirable because the meshes of the wire net are likely to be not uniform. 90

I claim:—

1. A device of the character described comprising a hat pin provided at one end with an enlargement, a member fashioned with an opening adapted to receive said enlargement and a spring wire including parallel sections cooperating with said opening to secure said enlargement to said member, said sections crossing and closer together than said opening and adapted to 100 be spread apart when said pin enlargement is forced into place.

2. A device of the character described comprising a ring adapted to be secured to one side of a hat, said ring carrying a cross 105 strip capable of limited turning movement, said strip in turn carrying a tubular portion for the reception of the shank of a hat pin, and means for securing the inserted end of the pin to the opposite side of the 110 hat.

3. A device of the character described comprising a ring member adapted to be secured to one side of a hat, said ring carrying an integral cross strip capable of limited 115 turning movement, said strip in turn carrying an integral tubular portion for the reception of the shank of a hat pin, and complementary engaging means on one end of said pin and on the other side of said 120 hat respectively.

4. A device of the character described comprising a member to be secured to one side of a hat and formed of a concavo-convex part and a ring shaped part, one of 125 said parts carrying a guide for the stem of a hat pin, said guide being adapted to be inserted through one side of the hat, the other of said parts being provided with an opening through which said stem may be 130

passed whereby additionally to guide, and a device on the opposite side of the hat for engaging the end of the pin.

5 A device of the character described comprising a stamping composed of spring metal to be secured to so that a part projects through one side of a hat and formed of two relatively flexible parts, adapted to assume various positions relatively to each

other and to be secured together in one position, having apertures adapted to align and said stamping serving as a double guide for spaced sections of the stem of a hat pin, and a device on the opposite side of the hat for engaging the pointed end of the pin. 10

Signed by me this 3rd day of July, 1920. 15

HERMAN MUEHLE.
